C. C. SEABORN.

PORTABLE POWER OPERATED TOOL HOLDER.
APPLICATION FILED MAR. 20, 1920.

1,400,774.

Patented Dec. 20, 1921.

UNITED STATES PATENT OFFICE.

CHARLES C. SEABORN, OF PORTLAND, OREGON.

PORTABLE POWER-OPERATED TOOL-HOLDER.

1,400,774.

Specification of Letters Patent. Patented Dec. 20, 1921.

Application filed March 20, 1920. Serial No. 367,341.

To all whom it may concern:

Be it known that I, CHARLES C. SEABORN, a citizen of the United States, residing at Portland, in the county of Multnomah and 5 State of Oregon, have invented certain new and useful Improvements in Portable Power-Operated Tool-Holders, of which the following is a specification.

This invention relates to tools, and the 10 primary object of the invention is to provide an improved power operated device with which a plurality of different kinds of tools may be associated, so that the device can be used for various purposes, such 15 as a shoe shiner, a grinder, a drill, a buffer, a floor polisher, a veterinary tooth grinder, a sand paperer, and the like.

Another object of the invention is to provide an improved power operated device of 20 the above character having an improved means for holding the tools detachably in position, so that the same can be conveniently and quickly removed or associated with the device when desired.

25 A further object of the invention is to provide an improved device embodying a portable casing having a handle attached thereto and supporting a pair of operatively connected, angularly related shafts, one of 30 the shafts having means for connecting various types of tools therewith and the other shaft having connected thereto a flexible shaft driven by a motor, the motor being positioned at any desired point.

35 A further object of the invention is to provide a clutch mechanism for connecting or disconnecting the driven shaft from the driving shaft in the casing, so that the operation of the tool can be stopped when desired, without stopping the operation of the 40 motor.

A still further object of the invention is to provide an improved device which is especially adapted for shining shoes, so that 45 the laborious method now in vogue of shining shoes by hand may be eliminated.

A still further object of the invention is to provide an improved device of the above character which is durable and efficient in 50 use, one that is simple and easy to manufacture, and one which can be placed upon the market at a reasonable cost.

55 Other objects of the invention will appear in the following detailed description taken in connection with the drawings, forming

a part of this specification, in which drawings:

Figure 1 is a central longitudinal section through the improved device, showing a rotary shoe shining brush operatively connected thereto.

Fig. 2 is a fragmentary longitudinal section through the device taken at right angles to Fig. 1.

Fig. 3 is a detail section taken on the line 65 3-3 of Fig. 1.

Fig. 4 is a detail perspective view of the member for operating the clutch mechanism.

Referring to the drawings in detail, wherein similar reference characters designate 70 corresponding parts throughout the several views, the letter A indicates the improved apparatus having a rotary shoe shining brush B associated therewith. While a shoe shining brush B has been 75 shown in connection with the improved device A, it is to be understood that any type of tool may be associated therewith as may be desired.

The improved device A includes a casing 80 5 having a pair of right angularly related bearings 6 and 7 which are connected together by a substantially semi-spherical wall 8. The bearings 6 and 7 are adapted respectively to rotatably support the driven 85 shaft 9 and the drive shaft 10. The inner terminals of the driven shaft 9 and the driving shaft 10 extend into the substantially semi-spherical wall 8, and the same are operatively connected together by a pair of 90 beveled gears 11 and 12. The gear 11 is rigidly secured to the shaft 9 for movement therewith, while the gear 12 is rotatably mounted on the shaft 10 for a purpose which will be hereinafter more fully described. 95 Both of the gears 11 and 12 are prevented from slipping off the terminals of the shaft by retaining screws 13 which are threaded into the inner ends of the shafts 9 and 10. A substantially semi-spherical cap 14 100 encloses the gears and is connected to the semi-spherical wall 8 by suitable screws or the like 15 which extend through the outwardly extending flange 16 formed on the edge of the cap 14 and into the bearings 6 and 7. 105 The bearing 7 has its outer end provided with a relatively large bore 17, a portion of which is threaded for the externally threaded reduced portion 18 of the handle 19 by means of which the blackening brush B or 110

other device may be brought into engagement with the work. The shaft 10 has keyed or otherwise secured thereto the washer 20, the outer face of which bears 5 against suitable bearings 21, which in turn bear against the rear wall of the enlarged portion of the bore 17 of the bearing 7 and against the outer wall of the reduced portion 18 of the handle 19. The handle 19 10 has a metallic sleeve 22 extending longitudinally therethrough which rotatably receives the driving shaft 10. The inner terminal of the metallic sleeve 22 can be threaded into engagement with the handle 19 if so desired.

The outer terminal of the sleeve 22 protrudes beyond the rear end of the handle 19 and has keyed or otherwise secured thereto a bearing 24 in which is rotatably mounted 20 a coupling 25 secured to the flexible shaft 26. The flexible shaft 26 may be secured to the armature shaft of any preferred type of electric motor (not shown). The rear end 25 of the driving shaft 10 extends into the bearing 24 and has a reduced extension 27 formed thereon which is connected to the coupling 25 in any preferred manner. The upper end of the bearing 24 may carry inwardly extending teeth 28 for biting into 30 the rear end of the handle 19 and thereby prevent movement of the sleeve 22 and bearing 24 in relation thereto. The outer portion of the bearing 6 is enlarged as at 29 and has rotatably mounted therein the 35 cylindrical block 30 keyed or otherwise secured to the outer terminal of the driven shaft 9 which terminates in the enlarged portion of the bearing. Suitable ball bearings are interposed between the cylindrical 40 block 30, and the wall of the enlarged portion of the bore 29 of the bearing 6 so as to permit free rotation of the block therein. The shaft 9 has also keyed or otherwise secured thereto the collar 9' which engages 45 the inner face of the bearing 6 and prevents lateral movement of the shaft in the bearing. Suitable ball bearings 10' are interposed between the collar 9' and the bearing 6 so as to permit the free unimpeded movement 50 of the collar in the bearing. The outer end of the cylindrical block 30 has threaded therein the sleeve 31, which rotatably supports the ring 32 for controlling the locking mechanism 33 for the tool shank or 55 shaft as will be hereinafter more fully described. The ring 32 is provided with a rearwardly extending flange 34 which engages the outer surface of the cylindrical block 30 and the outer edge of the bearing 6. The outer end of the sleeve 31 carries an 60 outwardly extending annular flange 35 which engages the spacer washer 36, which engages the forward face of the rotating ring 32. The locking means 33 for holding 65 the tools in operative position in relation to

the apparatus includes a dog 37, which is secured to a semi-circular leaf spring 38, which has its outer end riveted or otherwise secured as at 39 to the sleeve 31. The rotating ring 32 has a slot 40 which gradually increases in depth toward one end, and it can be seen that when the ring 32 is turned in one direction the same will compress the leaf spring 38 and force the dog 37 inwardly and when the ring is turned in the opposite direction the spring will be permitted to flex and move outwardly and move the dog outwardly. The sleeve 31 is provided with an aperture 42 through which the dog 37 is adapted to ride. The inner end of the dog 37 is adapted to fit into a recess 43 formed in the spindle or shaft 44 of the blackening brush or any other type of tool. When the dog is forced inwardly into engagement with the recess, it can be seen that accidental displacement of the spindle or shaft out of the sleeve is eliminated. To prevent the accidental rotation of the ring 32 when the dog is in operative engagement with the shaft 44, an inwardly extending tip 45 is 45 formed on the inner surface of the recess 40 which is adapted to engage the forward portion of the dog and prevent accidental movement thereof. The lower end of the gear wheel 12 is provided with a clutch face 45' which is adapted to be engaged by the movable clutch section 46, which is splined on the driving shaft 10. The movable clutch section 46 is provided with an annular groove 47 in which is rotatably mounted the 50 fork member 48, which is carried by the shank 49 slidably mounted in the bearing 6. The shank 49 has secured to its rear end the thumb piece 50 so that the operator may readily move the shank so as to throw the movable clutch section 46 into or out of engagement with the clutch section 45 carried by the gear wheel 12. Thus it will be seen that when the clutch section 46 moves into engagement with the gear wheel 12, the same will be rotated with the drive shaft 10 for actuating the shaft 9. The shank 49 is frictionally held against accidental movement by means of an expansion coil spring 55 100 which is confined in a recess in the bearing 6 and engaged against the shank so as to normally exert a pressure thereon.

The blackening brush B as shown consists of a core 52 which is secured on the spindle or shaft 44, and this core 52 has secured thereto the brush tufts 53.

In operation of the improved tool, the motor (not shown) is started in the ordinary manner, and the clutch section 46 moved into engagement with the clutch section 45' carried by the gear wheel 12, which will rotate the spindle 44. The brush tufts 53 are then moved into engagement with the shoe to be shined, and the quickly rotating brush tufts will effectively polish the shoe. It can be 115 120 125 130

readily seen that by rotating the ring 32 the dog 37 will be moved out of engagement with the shaft 44 thereby permitting the easy and quick removal thereof so that other types of tools may be associated with the device.

Changes in details may be made without departing from the spirit or scope of my invention; but,

10 I claim:

1. In a portable power operated device, a bearing, a driven shaft rotatably carried by the bearing, the bearing having an enlarged bore therein, a cylindrical block rotatably mounted in the bore and secured to said shaft, a rotatable ring carried by the block, the block being arranged to receive a tool spindle, a dog arranged to engage the tool spindle, and means for actuating the 20 dog by said ring.

2. In a portable power operated device, a bearing, a driven shaft rotatably mounted in the bearing, the bearing having an enlarged bore, a cylindrical block rotatably mounted in the bore and secured to said shaft, a tool spindle arranged to fit in said block and engage said driven shaft, a sleeve secured to said block and arranged to receive said spindle, a ring rotatably carried by the

sleeve and block, a leaf spring secured to the sleeve, a dog carried by the leaf spring and arranged to extend through said sleeve, the spindle having a socket therein arranged to receive the dog, the ring having a slot therein for the reception of said spring and dog, 35 the slot being gradually tapered toward one end thereof.

3. In a portable power operated device, a bearing, a driven shaft rotatably mounted in the bearing, the bearing having an enlarged bore, a cylindrical block rotatably mounted in the bore and secured to said shaft, a tool spindle arranged to fit in said block and engage said driven shaft, a sleeve secured to said block and arranged to receive 40 said spindle, a ring rotatably carried by the sleeve and block, a leaf spring secured to the sleeve, a dog carried by the leaf spring and arranged to extend through said sleeve, the spindle having a socket therein arranged to 45 receive the dog, the ring having a slot therein for the reception of said spring and dog, the slot being gradually tapered toward one end thereof, and means formed on the wall of said slot for engaging the dog to prevent 50 accidental rotation of the ring.

CHARLES C. SEABORN.
